UNITED STATES PATENT OFFICE.

AMOS S. BLAKE, OF WATERBURY, CONNECTICUT.

IMPROVEMENT IN PULLEYS.

Specification forming part of Letters Patent No. **59,172**, dated October 30, 1866.

To all whom it may concern:

Be it known that I, AMOS S. BLAKE, of Waterbury, in the county of New Haven and State of Connecticut, have invented a new and Improved Pulley; and I do hereby declare that the following is a full, clear, and exact description thereof, which will enable others skilled in the art to make and use the same, reference being had to the accompanying drawings, forming part of this specification, in which—

Figure 1 is a front elevation of my invention. Fig. 2 is a transverse vertical section taken on the line *x x*, Fig. 1.

Similar letters of reference indicate like parts.

This invention is adapted particularly for closing doors, gates, &c., where weights are employed.

My invention consists in a swivel sheave-frame, having its bearings in arms arranged at an angle with the bed-plate, by which the device is attached to the post of the gate or casing of the door, or elsewhere, in such manner that the rope which passes over the sheave will not come in contact with the said plate, whether the plate be affixed in a horizontal or vertical position, thereby giving to the sheave-frame the capacity of adjusting itself to the varying direction or draw of the cord.

A designates the bed-plate, and this is provided with a suitable number of perforations, for attaching it by nails or screws to any surface on which it is to be secured. *B B* are two arms, which extend out from the plate *A* in a direction to bring their extreme ends be-

yond the inner edge of the bed-plate *A*. Into these arms is journaled the sheave-frame *C* in such manner as to allow it a rotary motion. The sheave or roller *D* is pivoted between the two cheeks of the sheave-frame in any suitable way.

I have constructed the sides or cheeks of the frame with ears *a a*, projecting outward from each in opposite directions, as shown clearly in Fig. 1. These ears serve as guides for the rope to keep it from flying out of the groove in the periphery of the sheave, as is evident.

It will be noticed that by setting this roller in a swivel-frame it is allowed every motion necessary to allow it to vary according to the direction of the draw of the rope passing over it, and hence it operates much more perfectly than were it hung in rigid bearings, and that by journaling the swivel-frame in arms *B B*, whose ends project out beyond the bed-plate *A*, when the bed-plate is secured in a horizontal position, no interference of the rope with the bed-plate can occur.

What I claim as new, and desire to secure by Letters Patent, is—

1. Journaling a sheave or roller, *D*, in a swivel-frame, *C*, substantially as and for the purpose specified.

2. The combination of the swivel sheave-frame *C* with the angular arms *B B* and bed-plate *A*, substantially as shown and described.

AMOS S. BLAKE.
